UNITED STATES PATENT OFFICE.

HARRY HUEBNER, OF PHILADELPHIA, PENNSYLVANIA.

CLOTHES-LINE REEL.

SPECIFICATION forming part of Letters Patent No. 664,640, dated December 25, 1900.

Application filed June 6, 1900. Serial No. 19,210. (No model.)

To all whom it may concern:

Be it known that I, HARRY HUEBNER, a citizen of the United States, residing at Philadelphia, county of Philadelphia, and State of Pennsylvania, have invented a new and useful Improvement in Clothes-Line Reels, of which the following is a specification.

My invention relates to a new and useful improvement in clothes-line reels, and has for its object to provide a simple and effective device of this description upon which a clothes-line may be wound when not in use and from which it may be readily withdrawn when desired for use.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a perspective of a reel made in accordance with my improvement; Fig. 2, a section thereof; Fig. 3, a perspective showing a slightly-modified form of the revolving member, and Fig. 4 a detail view showing the spring-washer which acts as a brake to retard the rotations of the revolving member.

In carrying out my invention as here embodied, A represents a spindle which is secured within the handle B, and also secured in this handle is a guide C, which is composed of a single piece of wire so bent as to form the loop D, the sections of the guide being held in proper relation by the clip E. The securing-pin A', passed through the handle, spindle, and guide-wire, serves to retain the several parts in their relative positions.

F represents the revolving member or reel, which is composed of two disks connected together by the hollow metal hub G, and this revolving member is journaled upon the spindle A and has a crank-handle H attached thereto, by means of which it may be revolved for winding the line upon the reel. A hole I is formed in the metal hub, into which one

end of the line may be passed, and thereby held while being wound upon the reel, and the line is guided by being passed through the loop D on its way to the reel.

A spring-washer J is passed over the end 55 of the spindle and held in place by the cotter-pin K, which causes said washer to bear with some force against the reel, which will prevent the reel from revolving too readily when hauling out the line, as will be readily understood.

In practice when the line is out of use it is wound upon the reel by the person grasping the handle B with one hand and revolving the member F with the other hand through 65 the medium of the crank-handle H, after which the reel and line may be stored or suspended from a suitable hook or nail until again needed.

In Fig. 3 the revolving member L, instead 70 of being circular, as above described in connection with Figs. 1 and 2, is composed of two side strips M, connected together by the curved strips N, which are riveted at O to the first-named strips. The curved strips 75 are connected together at their centers by the short member P, and this revolving member is journaled upon the spindle A in the same manner as the revolving member F.

Having thus fully described my invention, 80 what I claim as new and useful is—

In a clothes-line reel, a handle, a spindle secured therein at one end, a revolving member journaled upon the spindle, a guide consisting of a single piece of wire, so bent as to 85 form a loop; said guide having its ends seated in the handle, and a looped portion bent at an angle with relation to the ends and supported above the revolving member, and a securing-pin run through the handle, spindle, 90 and the guide-wire embedded in the handle, substantially as described.

In testimony whereof I have hereunto affixed my signature in the presence of two subscribing witnesses.

HARRY HUEBNER.
